UNITED STATES PATENT OFFICE

2,434,716

SHIRT BOARD

Sidney Ralph, Jacksonville, Fla.

Application March 10, 1945, Serial No. 582,133

4 Claims. (Cl. 223—71)

1

My present invention, in its broad aspect, has to do with improvements in shirt boards, and by that I mean stiffeners and folding supports for shirts and the like whereby the shirt, including the collar, and the like is properly maintained in a folded and unwrinkled condition, and properly and attractively displayed. More particularly it is my purpose to provide as an integral element of a shirt board a collar and neck band support, the same being die-cut in a simple operation from the material of the board. The advantages of this improved construction are many; for instance: the board is complete as a unit with collar and neck band supports, whereas heretofore separate strips have been used for this purpose; the board represents a saving in material and manufacturing costs; the collar and neck band supports are automatically positioned and maintained in the most advantageous position, and will not become deranged or the like; and the device may be manufactured and sold at a relatively small cost, and applied to a shirt with a saving in labor and the like, over devices heretofore used.

Other and equally important objects and advantages of my invention will be apparent from the following description and drawings, but it is pointed out that changes in form, size, shape, materials, and construction and arrangement of parts are within the purview of my broad inventive concept and the scope of the appended claims.

In the drawings wherein I have illustrated preferred forms of my invention;

Figure 1 is a perspective view, partly fragmentary, showing my device applied to the collar and neck band of a shirt;

Figure 2 is a plan view of the blank from which my device is formed;

Figure 3 is a perspective view, partly fragmentary of the collar wing and neck band supporting elements;

Figure 4 is a section on the line 4—4 of Figure 1;

Figure 5 is a perspective view, partly fragmentary of means for supporting the back of the collar as well as the front parts of the collar;

Figure 6 is a plan view of the blank from which the type shown in Figure 5 is formed;

Figure 7 is a diagrammatic detail showing the manner for folding the collar wing and neck band supports, and

Figure 8 is a diagrammatic view showing how the support for the back of the collar is folded.

In connection with the following detailed de-

scription, it is to be noted that in packing shirts for storage or delivery in laundries and the like, unless support is given the collars, they are likely to become crushed. My device is therefore especially indicated for use in laundries in folding, packing, or storing and delivering shirts.

The numeral 1 designates a rectangular, elongated sheet of cardboard, or the like, which in operation is disposed beneath the shirt front, extending at the side edges 2 to about the point where the shirt 3 is folded back and suitably pinned or the like to present it in proper condition for sale. As shown in Figure 2, a rectangular area 4 is die cut near the top of the board to provide a pair of parallel or concentric arcuate strips 5 and 6 connected together at their medial points as at 7; the strip 6 being scored at 8 to facilitate folding at the connected point. The arcuate strip 6 is connected by an elongated web 9 with the board. The top edge 10 of the board is disposed snugly at the shoulders of the shirt as shown in Figure 1.

To properly support and stiffen the neck band and collar of the shirt, the strip 6 is folded forwardly as shown in Figures 3 and 4, and the arcuate strip 5 is turned over and down at the medial connecting part 7. The web 9 lies between the strips 5 and 6.

In operation, the strip 6 lies back of the neck band at the front of the shirt, and the medial connecting part 7 folds over and down about the part between the collar wings 11 to dispose the arcuate strip 5 beneath and in back of the collar wings to support them in proper finished shape and prevent wrinkling.

As shown in Figures 5 to 8, a narrow, rectangular strip 12 may be provided at the top of the board 1 and connected with the board at its medial point 13, and the board is scored at 14 to assist bending the medial connecting part. The strip 12 is disposed against the neck band at the back of the collar to hold the shape of the collar. In placing the strip 12 in position it is folded upwardly from the board as shown in Figure 8.

From the foregoing it is believed that the operation, advantages and objects of my invention will be apparent, but it is again pointed out and emphasized that interpretation of the scope of my invention should only be conclusive when made in the light of the subjoined claims.

I claim:

1. A shirt board, comprising concentric arcuate strips cut-out from the board, said strips being connected with each other and with the board, and foldable with respect to each other

3

and the board to support the collar wings and neck band of a shirt carried by the board.

2. A shirt board, comprising two arcuate strips cut out from the board and connected with each other and with the board, and foldable with respect to each other and the board to support the collar wings and neck band of a shirt carried by the board, and a rectangular strip connected between its ends with the board at the top end thereof and foldable with respect to the board to support the back of a collar.

3. A shirt board, comprising arcuate strips cut-out from the board, the strips being connected with each other medially their ends and one side of said strips being connected with the board intermediate its ends, and said strips being foldable with respect to each other and the board to support the collar wings and neckband of a shirt carried by the board.

4. A shirt board comprising two parallel strips 20

4

cut-out from the board, said strips being connected with each other medially their ends, and an elongated web connecting one of the strips with the board, said strips and said web being foldable with respect to each other and the board to support in finished shape the collar wings and neckband of a shirt carried by the board.

SIDNEY RALPH.
